UNITED STATES PATENT OFFICE.

ALEXANDER W. BEERS, OF BAYONNE, NEW JERSEY.

FOLDING BOX.

1,032,645.

Specification of Letters Patent.

Patented July 16, 1912.

Application filed March 2, 1911. Serial No. 611,765.

To all whom it may concern:

Be it known that I, ALEXANDER W. BEERS, a citizen of the United States, and residing at Bayonne, in the State of New Jersey, have invented certain new and useful Improvements in Folding Boxes, of which the following is a specification, such as will enable those skilled in the art to which it appertains to make and use the same.

10 This invention relates to folding or knock down boxes and the object thereof is to provide an improved box of this class, designed for use by tailors and others in packing or shipping clothes or other articles, 15 or which may be used for various purposes; a further object being to provide a box of the class specified, composed of top and bottom parts which are adapted to be folded compactly together when disconnected, and 20 which are similar in form when so folded and approximately of the same dimensions; a still further object being to provide a box of the class specified which will be strong and durable, and which is preferably composed 25 of fibrous material, such as pasteboard, cardboard or the like.

The invention is fully disclosed in the following specification, of which the accompanying drawing forms a part, in which the 30 separate parts of my improvement are designated by suitable reference characters in each of the views, and in which:

Figure 1 is a plan view of a blank from which the top part of my improved box is 35 formed; Fig. 2, a similar view of a blank from which the bottom part of my improved box is formed; Fig. 3, a plan view of one end portion of the top part of the box complete; Fig. 4, a view similar to Fig. 3 but 40 showing the bottom part of the box; Fig. 5, a view looking in the direction of the arrow 5 of Fig. 3; Fig. 6 a perspective view of one end of the top part of the box partly folded; Fig. 7 a view of the part shown in 45 Fig. 6 completely folded; Fig. 8 a view similar to Fig. 6, but showing one end portion of the bottom part of the box; Fig. 9 a view similar to Fig. 7 of the construction shown in Fig. 8; Fig. 10 a horizontal section 50 of one end portion of the box complete; Fig. 11 a section on the line 11-11 of Fig. 3; Fig. 12 a section on the line 12-12 of Fig. 11, and Fig. 13 a sectional detailed view on the line 13-13 of Fig. 4.

55 In Fig. 1 I have shown a blank from which the top part of the box is formed,

comprising a body portion a , folding side members a^2 and folding end members a^3 . Between the folding end members a^3 and the top a are score or folding lines a^4 and 60 between the folding side members a^2 and the top a are formed longitudinal grooves a^5 shown in section in Fig. 12, and also clearly shown in Fig. 6. The ends of the sides a^2 are scored diagonally as at a^6 to form triangular parts a^7 , and the end portions a^8 are scored at a^9 defining rectangular end portions a^9 , and between the end portions a^9 of the folding end members a^3 , and the folding side members a^2 are transverse slits or 65 openings a^{10} . In forming the top part of the box from the blank shown in Fig. 1, the triangular end portions a^9 of the folding end members a^3 are folded inside the end portions of the folding side members a^2 , 70 as clearly shown in Figs. 6 and 11, and the upper outer corner portions a^{11} thereof are secured to the triangular end portions a^7 of the folding side members, this connection being preferably made by means of wire 75 staples a^{12} , but said connection may be made in any desired manner. This leaves the lower triangular portions a^{13} of the parts a^9 free, as will be readily understood. With 80 this construction, the folding side members a^2 and end members a^3 of the top of the box may be folded flat on the body a , as clearly indicated in Figs. 6 and 7 and in this operation, the end portions of the folding side members a^2 fold inwardly on the score or 85 folding lines a^6 , while the bottom inner portions a^{13} of the end portions a^9 of the folding end members a^3 fold inwardly and 90 lie flat on the said folding members a^3 , as will be readily understood and as clearly 95 indicated in Figs. 6 and 7.

When the parts or folding side members a^2 and end members a^3 are opened up so as to prepare the top of the box for use, the lower inner corner portions a^{13} of the end 100 portions a^9 of the folding end members a^3 , swing outwardly over the body a and the bottom edges thereof enter the grooves a^5 as clearly shown in Figs. 3 and 12, and said parts a^9 or the bottom inner edges thereof 105 form a lock to hold the separate parts of the top of the box in proper form.

The bottom part of the box is formed from a blank, comprising a body portion b , folding side members b^2 , and folding end 110 members b^3 , and between the body b and side members b^2 are score or folding lines

b^4 , while between the folding end members b^3 and body b are grooves b^6 similar to the grooves a^5 . The folding end members b^3 are substantially of a length equal to the width of the body b and are scored diagonally as at b^6 , defining triangular folding portions b^7 , and the folding side members b^2 are provided with rectangular end portions b^8 , between which and said side members are score or folding lines b^9 and the folding end portions b^8 of the side members b^2 overlap the folding end portions b^3 , and are separated from said folding end portions by slits or openings b^{10} . The folding of the blank to form the bottom part of the box is the same as the folding of the blank to form the top part thereof, and in this operation wire staples b^{11} are employed to secure the upper inner corners of the parts b^8 , the lower or inner corners b^{12} of said parts being left free. With this construction of the bottom part of the box, the side members b^2 and end members b^3 , may be folded inwardly onto the body b as shown in Figs. 8 and 9, and in this operation the end members b^3 fold inwardly on the score lines b^6 and the end parts b^8 of the folding side members b^2 fit snugly on or under the ends of the said side members, as clearly shown in Figs. 8 and 9, and when the folding side members b^2 and end members b^3 are raised so as to open up the bottom part of the box and put it into condition for use, the lower inner corners b^{12} of the parts b^8 slide out over the body b , and the lower edges thereof enter the grooves b^5 , said grooves, in cross section, being the same as the grooves a^5 in the body a of the top of the box and thus the parts b^9 form locks to hold the folding side and end portions of the bottom part of the box in upright position.

When the top and bottom parts of the box are constructed as shown and described, the folding side members of the top part of the box are reinforced at the ends thereof by the parts a^9 , and the folding end members of the bottom part of the box are reinforced at the ends thereof by the parts b^8 , and this forms a double reinforcement for all corners of the box as will be readily understood. The said parts a^9 and b^8 form locks which operate in connection with the grooves a^5 and b^5 , to hold the separate parts of the box in proper form at all times.

From the drawing and foregoing description, it will be seen that the blanks, from which the top and bottom parts of the box are constructed, are both exactly rectangu-

lar in form and the opposite edges thereof are parallel and by reason of this fact there will be no waste of material in the manufacture of my improved box and said box may be made at the lowest possible cost.

Having fully described my invention, what I claim as new, and desire to secure by Letters Patent, is:—

1. A knockdown box member composed of a blank which is rectangular in form and the opposite edges of which are parallel, said blank comprising a rectangular body portion, a pair of folding side members and a pair of folding end members, said blank being also provided between the body thereof and one pair of folding members with parallel scorings, forming folding lines and locking grooves, said pair of folding members being also provided at the ends thereof with triangular folding parts, and the other pair of said folding members being provided at the ends thereof with rectangular folding parts which are folded inwardly of said triangular folding parts and the upper outer corners of which are secured thereto and the lower inner corners of which are left free and the bottom edges thereof being adapted to enter said locking grooves.

2. A knockdown box composed of top and bottom parts each of which consists of a blank which is rectangular in form and the opposite edges of which are parallel, said blanks being each composed of a central body portion having folding side members and folding end members, said blanks being also provided between the body thereof and one pair of folding members with parallel scorings forming folding lines and locking grooves, one pair of folding members of each blank being also provided at the ends thereof with triangular folding parts, and the other pair of said folding members of each blank being each provided at the ends thereof with rectangular folding parts, which are folded inwardly of said triangular folding parts and the upper outer corners of which are secured thereto, and the lower inner corners being left free, and the bottom edges thereof being adapted to enter said locking grooves.

In testimony that I claim the foregoing as my invention I have signed my name in presence of the subscribing witnesses this 1st day of March 1911.

ALEXANDER W. BEERS.
